UNITED STATES PATENT OFFICE.

PETER F. LABAN, OF ALTONA, GERMANY, ASSIGNOR TO JULIUS LABAN, OF BROOKLYN, NEW YORK.

VALVE-LUBRICATOR.

SPECIFICATION forming part of Letters Patent No. 706,963, dated August 12, 1902.

Application filed April 12, 1902. Serial No. 102,558. (No model.)

To all whom it may concern:

Be it known that I, PETER F. LABAN, a subject of the Emperor of Germany, residing at Altona-on-the-Elbe, Germany, have invented 5 certain new and useful Improvements in Valve-Lubricators, of which the following is a full, clear, and exact description.

My invention relates to improvements in valve-lubricators; and the object that I have 10 to in view is the provision of means for automatically supplying a lubricant to the valve-seat and other internal parts of the structure during the working or operation of the valve itself.

15 According to my invention the lubricating liquid is distributed by the movement or action of the valve to different portions of the valve-seat and between the ports in the chest, and at the same time the valve is so constructed 20 ed that it will always occupy an operative relation to the point of liquid-feed, so as to be supplied from the latter, notwithstanding the travel or movement of the valve. The lubricant is distributed through the valve- 25 chest by open or exposed ducts or channels, so that it may be taken up by the steam and carried to all parts which require lubrication.

The improvements involve an exceedingly simple construction of valve and valve-seat, 30 they are reliable and efficient in the distribution of the lubricant, and they can be embodied at a moderate cost in the manufacture of the valve mechanism.

With these ends in view the invention consists in the novel construction, arrangement, 35 and combination of parts, which will be hereinafter fully described, and the actual scope of the invention will be defined by the claims.

Reference is to be had to the accompanying 40 drawings, forming part of this specification, in which similar characters of reference indicate corresponding parts in all the figures.

Figure 1 is a vertical transverse section through a valve-chest and an ordinary slide- 45 valve equipped with lubricating devices as contemplated by my invention. Fig. 2 is a sectional plan view in the plane of the dotted line 2 2 of Fig. 1, a part of the valve being broken away in order to more clearly show 50 the valve-seat. Fig. 3 is a vertical transverse section taken in the plane of the dotted line

3 3 of Fig. 1. Figs. 4 and 5 are vertical transverse sections illustrating different positions of the slide-valve in order to bring its lubricating feed-passages into registration with 55 different distribution-channels in the face of the valve-seat.

In order that others may understand my invention, I have illustrated it as applied to an ordinary locomotive-engine valve. 60

The valve-chest is indicated by the numeral 5, and within it is the ordinary valve-seat 6, the same being provided with the inlet-ports 7 7^a and the exhaust-port 8. On this valve-seat rests the ordinary slide valve 65 9, except that said valve is modified somewhat in its construction in order to embody my improvements. This valve is provided with the usual passages 10 11, adapted to register with the passages 7 7^a and 8 in the regular way, thereby controlling the admission of live steam to the piston-cylinder and the escape of the exhaust-steam from said cylinder. 70

One of the improvements contemplated by 75 my invention is a feed-trough 12, the same being formed by cutting a recess in the top face of the valve 9, which recess extends across the valve on a line close to and parallel with one side edge of the valve, as clearly 80 shown by Figs. 1 and 2. The valve is furthermore provided with feed-passages 13, any desired number of which may be formed in said valve in order to conduct the lubricant from the feed-trough 12 to the bottom face of 85 the valve. As shown by Figs. 2 and 3 of the drawings, I employ two of these feed-passages, which extend vertically through the valve and which have communication at their upper ends with the feed-trough; but it is 90 evident that the number of these passages may be varied.

The lubricant is supplied in regulated quantities to the interior of the valve-chest by a feed-pipe 14, the latter extending from a reservoir or any other suitable source of supply 95 adapted to be charged or filled with lubricant of a proper kind. This feed-pipe 14 passes through a bushing 15 and has a steam-tight connection with the valve-chest by means of 100 an ordinary stuffing-box 16. The inner portion of this feed-pipe is coupled to or termi-

nates in an overhanging discharge-nozzle 17, the latter being situated within the chamber of the valve-chest 5 and arranged to discharge the liquid directly into the trough 12, which, 5 as before mentioned, is provided in the upper face of the slidable valve 9.

To secure a more uniform and thorough distribution of the lubricant within the valve-chest and in order to lubricate the wearing- 10 surfaces of the valve and the valve-seat, I employ the distributing-channels 18 18^a and 19 19^a. These distributing-channels are formed in the upper face of the valve-seat 6, and they extend across the valve-chest on 15 lines parallel with the edges of the steam inlet and exhaust ports. The channel 18 is at one side of the port 7^a, the channel 19 is between the ports 7^a and 8, the channel 18^a lies between the ports 7 and 8, and the channel 20 19^a lies at one side of the port 7, all as clearly shown by Figs. 2, 4, and 5 of the drawings. The feed-passages 13 are so related to the series 25 of distributing-channels that on the adjustment of the valve to the limit of its movement in one direction and to the position shown by Fig. 5 said passages 13 will be brought into registration with the distributing-channels 19 19^a. The movement of the valve in the opposite direction brings the passages 13 into 30 registration with the other pair of distributing-channels 18 18^a, as shown by Fig. 4. From this description it will be seen that the distributing-passages in the valve alternately 35 register with one pair or the other of the distributing-channels in the valve-seat, and thus the lubricant which is contained in the trough 12 of the valve will be supplied at regular intervals to the distributing-channels. The lubricant may be fed continuously to the trough 40 in the valve, notwithstanding the movement of the latter, because the valve slides in a path below the nozzle 17, whereby said nozzle may deliver the lubricant at all times to the trough of the valve. The lubricant which is supplied 45 to the distributing-channels by the operation or movement of the valve is adapted to overflow these channels and to spread itself over the engaging faces of the valve-seat and the valve, thereby thoroughly lubricating the 50 contacting surfaces which are most exposed to friction and wear. Furthermore, the lubricant which is contained in the distributing devices of the valve and the valve-seat

is exposed to the action of the steam which is supplied to and exhausted from the piston-cylinder, and some of the lubricant will be taken up by the steam, so as to be carried into the cylinder, thereby lubricating the working parts of the engine. 55

Having thus described my invention, I 60 claim as new and desire to secure by Letters Patent—

1. A valve-lubricator, comprising a series of distributing-channels in the exposed face of the valve-seat and adjacent to the steam-ports therein, a feed-trough in an exposed part of the valve, distributing-passages formed in the valve so as to communicate at all times with the feed-trough and adapted to register with different distributing-channels 70 on the movement of the valve, and means for supplying lubricant to said trough. 65

2. A valve-lubricator, comprising a valve-seat having parallel distributing-channels in the exposed surface thereof and between the series of ports, a valve having in its exposed face a trough and also provided with transverse channels which are normally in communication with said trough, said transverse channels arranged on the movement of the valve to register with different distributing-channels in the face of the valve-seat, and means for supplying lubricant to the distributing-trough. 75

3. A valve-lubricator comprising a valve-seat having distributing-channels in its exposed face and between the ports therein, a valve provided in its top face with a transverse trough, vertical passages in said valve, said passages communicating normally with the feed-trough and adapted to register with different distributing-channels on the movement of the valve, a feed-pipe having a nozzle disposed in overhanging relation to the feed-trough and adapted to deliver lubricant 95 thereto at all points in the movement of the valve, and means for making a steam-tight connection between the feed-pipe and the valve-chest. 85

In testimony whereof I have signed my name to this specification in the presence of two subscribing witnesses. 100

PETER F. LABAN.
